UNITED STATES PATENT OFFICE.

JOHN D. LOOG, OF NEW YORK, N. Y.

AUTOMATIC GRAPHITE-LUBRICATING SYSTEM FOR INTERNAL-COMBUSTION-ENGINE CYLINDERS.

1,353,055.

Specification of Letters Patent. Patented Sept. 14, 1920.

Application filed July 8, 1919. Serial No. 309,275.

To all whom it may concern:

Be it known that I, JOHN D. Loog, a citizen of the United States, and a resident of the city of New York, borough of the Bronx, 5 in the county of the Bronx and State of New York, have invented a new and Improved Automatic Graphite - Lubricating System for Internal - Combustion - Engine Cylinders, of which the following is a full, 10 clear, and exact description.

This invention relates to lubrication of combustion engines, particularly to an improved system of lubrication in which high grade, finely divided, flaked graphite is directly admitted into the cylinders of such engines without loss of compression and at a rate predetermined and proportioned to the diameter, stroke and speed of the piston.

Another object of the invention is to provide an improved lubricating system for cylinders of combustion engines which will operate satisfactory with one, or any number of cylinders of the different types of such engines, and to operate without the 25 necessity of structural changes of such engines, and of such construction that the improved lubricating system may be assembled and properly adjusted ready to be set up.

A further object of the invention is to 30 operate the system automatically by the suction stroke of the engine in such manner that the graphite may freely pass directly into the cylinders, without the possibility of clogging the ducts, and that the graphite 35 on reaching the cylinders there be distributed with the help of the inrushing gas-vapor on the walls of the cylinder where it forms a permanent lubricating film.

A still further object of the invention is 40 to provide means whereby a maximum charge of graphite may be admitted to help the priming operation, also to provide means for the general operation whereby a predetermined uniform charge is admitted continuously to maintain the permanent lubricating film above referred to.

In the accompanying drawings:

Figure 1 is a top plan view of an internal combustion engine with a lubricating system embodying the invention shown applied thereto.

Fig. 2 is a side view of the engine and lubricating system shown in Fig. 1, certain parts being shown in section for better illustrating the connection between the engine and the lubricating system.

Fig. 3 is an enlarged fragmentary sectional view through Fig. 2 on line 3—3.

Fig. 4 is a sectional view through Fig. 3 on line 4—4.

Fig. 4^a is a detailed view of a portion of the valve member.

Fig. 5 is a view similar to Fig. 4, but showing the parts in another position.

Fig. 6 is a fragmentary sectional view 65 showing the connection between the line pipes and the supply reservoir, the same embodying certain features of the invention.

Fig. 7 is a transverse sectional view through Fig. 4 on line 7—7.

Fig. 8 is a detailed view showing the end of the plunger control rod embodying certain features of the invention.

Fig. 9 is an enlarged face view of the regulating dial shown in section in Fig. 4.

Fig. 10 is an enlarged sectional view through Fig. 1, approximately on line 10—10.

Fig. 11 is a top plan view of a V-type of engine showing an embodiment of the invention applied thereto.

The character of the fuel used in combustion engines is fully known to the general public, the method of lubricating of the different parts is well provided for with 85 the exception of the cylinders. The lubrication of this one very important part of the engine is the sole object of this invention. The fact has to be admitted by all interested in the manufacture and use of 90 combustion engines that up to the present time the lubrication of the fourth, or as termed exhaust stroke of a four cycle engine is very problematical. This same fact refers to a two cycle engine where firing of 95 the charges takes place on every second stroke of the engine and in this case the compression stroke and part of the power stroke operate with very little of the lubricating oil left to form a lubricating film.

The extremely high temperature in the cylinders will consume all the oil present, as there are no lubricating oils produced having a flash point which will not be affected by the heat of 1400° to 3000° F. created by 105 the firing of the gas charges. To remedy this condition the addition of graphite to the lubricating oil is made possible by the invention described herein. Graphite has the quality to withstand heat, and will furnish an excellent lubricating film with the oil absorbed by it, as such a film is highly 110

viscous it forms a lubricant which will fill up all clearances and will furnish a lubricant for the piston during the firing stroke, as it will not burn up under the heat conditions created in any combustion engines, of which there are two principal groups, the explosive types and the slow burning Diesel types, a permanent lubricating film being retained in all these types. The heavy body of the lubricant automatically excludes superfluous lubricating oil from entering the cylinders, whereby all carbon deposits are eliminated, as the heat will gasify some of the oil constituting the lubricating film the released graphite will pass out with the exhaust, requiring continuous renewal of the oil and graphite film, which is provided for by the micrometric close regulation of feed. The reduction in consumption of oil will be found considerable, and will affect the cost of operation in proportion, as the consumption of graphite is only a trifle in proportion of the saving of oil effected. The presence of the graphite in the cylinders will not affect the proper process of explosion or slow burning of the gas charges, the small proportion of graphite which may find its way to the reservoir of the engine will only help the lubrication of the crank shaft. For illustration it may be stated that the standard supply port for automobile engines is of a 32" diameter divided into ten different stops by the valve member, this will fully illustrate the amount of graphite consumed with the lubrication described in this invention, the port being generally kept closed half way or less in proportion during normal operation.

40 The heavy viscous body of the lubricant above described will affect the compression of the engine favorably, as all parts of the cylinder will be kept filled up permitting close fitting rings so that none of the compression will be lost, and thereby permit the operation of the engine with lean charges of gas.

In the accompanying drawings one embodiment of the invention is shown in connection with a four cycle four cylinder engine as illustrated in Figs. 1 and 2, the type principally used on automobiles, trucks, and the like. As indicated in these figures the supply reservoir 1 is connected with a suitable control construction 2, which in turn is connected with the main line supply pipes 3 and 4 constituting line ducts extending across the respective cylinders of the engine. These line ducts are divided into sections, there being one section for each cylinder, and in the present instance four, two sections being connected with the controlling construction 2 and with the injecting fittings 16 of adjacent cylinders, while the other sections are connected to said fittings and

also to fittings in the end cylinders whereby the graphite may freely pass to all of the cylinders as required. The respective fittings 14 are identical and the respective fittings 16 are identical, in fact the fittings 14 and 16 are identical except that the fittings 16 have openings on opposite sides so as to have what may be termed an inlet section and an outlet section on the line duct, while the end fittings 14 have merely inlet openings. The particular construction interior of the fittings 14 and 16 is identical and illustrated more particularly in Fig. 10. This fitting has been found to be a desirable construction, but it will be understood that other forms and various modifications thereof could be used without departing from the spirit of the invention. As shown in Fig. 10, fitting 14 is provided with a T-union 14' having the usual union ring 10 so that when applying the union the priming cup 15 is removed from the engine and the union male section 10' is screwed in its place, after which the union ring 10 is tightened. This will complete the application of the union to the engine. To provide a proper priming, cup 15 is mounted on the upper end of the union 14' designed to act in the usual manner. This same operation is carried out on all of the cylinders and when completed the device is in condition for operation. In connection with the T-union 14 fittings 16 and 14 are used, consisting of valve chambers 9, same being threaded into the union as shown in Fig. 10, said chamber having a valve seat 19 for receiving the valve member 22, which valve member is provided with a valve rod or stem 21 which extends through the chamber and through an opening in the restricted end 20, which restricted end is also threaded exteriorly and provided with a socket for receiving the part of the spring 24. The extreme end of the stem 21 is provided with a groove for receiving a U-key 23, which key is of an old and well known construction, and consists of a form of a U-shaped straddling member engaging the groove on the stem 21 seated in a recessed washer 23. In order to prevent any leakage around the valve stem 21 and also to protect the spring 24 and associate parts, a cap 25 is threaded on to the restricted end 20. The valve 22, shown particularly in Fig. 10, is normally held seated by the spring 24 acting on washer 23, but is opened by the suction produced by the suction stroke of the piston. Valve 22 is provided and its function is to admit the graphite charges at a given time without the slightest loss to the compression of the engine, cap 25 being formed with a hexagon shaped nut, so that a wrench may be used thereon. It will be noted that the valve 22 remains seated during the compression, power and exhaust strokes of the

engine. During these three strokes the vibration of the engine will cause a sufficient quantity of graphite to pass through the port 31 hereinafter fully described and shown in Fig. 4, said graphite passing from reservoir 1 into the bore 29 in front of valve 30 to supply the desired graphite charge for the lubrication of the two cylinders which are fired together, and which are located on opposite sides of the reservoir. Referring to the supplying of the graphite to the ducts 3 and 4 it will be seen from Fig. 4 that the graphite will readily pass into and through port 31 by reason of the small volume of air passing through air port 31'. This air passes into the reservoir 1 and consequently prevents a vacuum forming therein so that the vibration of the engine will always cause a proper amount of graphite to pass freely through passage 31 into bore 29, and from thence be drawn into the respective cylinders. During the suction stroke the graphite will readily pass through the ducts 3 and 4 to the particular cylinders with the valve members 22 unseated. As soon as the pistons, on the suction stroke, reach their lower dead center the valves 22 will automatically close under the action of their springs 24 so that the flow of graphite into the cylinders will cease.

Referring more particularly to the controlling member 2, it will be seen from Figs. 4, 5 and 6 that it is provided with a casing 25 merging into a T-shaped extension 26 into which the line pipes or ducts 3 and 4 are screwed. The T-shaped extension 26 is also provided with an abutting flange 28 and an exteriorly threaded boss 27 located centrally in respect to the reservoir 1 and the ducts 3 and 4. This boss is hollowed out and is always in communication with passageway 31 so that the graphite may freely pass from the reservoir into the passageway 31 and pass into bore 29. The passageway 31 is arranged at an appreciable angle to the bore 29 and consequently the port or opening is elongated as it merges into bore 29. This is easily provided by running a small drill through the extension 26 so as to form both the passageways 31 and 31' which by one operation provides a passageway for the graphite and also a passageway for air to the reservoir. This arrangement is preferable, though if desired the passageway 31 could be made vertical or at some other angle than that shown, the object being to locate the opening of the port 31 well inward or away from the entrance of duct 3 so that it may be readily covered by the plunger 30 whenever desired. The valve member or plunger 30 fits the bore 29 in such a manner as to readily close the port or passageway 31 when moved thereover, though allowing the

passage of the full amount of air as hereinafter described when any of the pistons are on the suction stroke. Valve 30 is provided with a stem 32 having a groove in the outer end for receiving the U-key 35 which is held in place by a valve member 34 acted on by the spring 33 surrounding the stem 32 (Fig. 8). The valve member 34 is designed to engage its seat 34' formed on the interior part of the head 46, which head is provided with a notched flange 47 and with a sleeve 38 merging into a reduced portion (Fig. 4a). The reduced portion of said sleeve 38 is provided with an operating bore for stem 32, merging in an enlarged bore for the housing of spring 33, on the shoulder formed at the merging point of the two bores spring 33 bears with one end, the tension of said spring is held at the other end by valve member 34, keeping said valve member unseated normally. Bushing 39' is provided with flange 39 of a diameter to operate freely in bore 43 of casing 25, said bushing is threaded over the reduced end of sleeve 38, and fixed in its proper alinement on said sleeve by key 38', Fig. 4. Said bushing 39' is also externally threaded, with proportionate threads per inch, to effect a linear movement of plunger valve member 30 bearing against flange 39 acted on by spring 33, on a full turn of sleeve 38 carrying bushings 39', the extent of the linear movement of the plunger to equal the full diameter of post 31. Surrounding sleeve 38 and threaded to the bushing 39' is an auxiliary or outer sleeve 40, provided with flange 41. The spring 44 surrounds the auxiliary sleeve 40 and bears with one end against flange 41, the other end of spring 44 bears against nut 45, said nut threaded into casing 25, so as to normally hold the flange 41 of sleeve 40 against the shoulder 42 of casing 25, though allowing the same to be moved therefrom as shown in Fig. 5, when pulled in direct line 110 therefrom. In order to allow this reciprocating movement of auxiliary sleeve 40 without a rotating movement, a groove 40' is machined from the end of said sleeve 40 extending across nut 45, as shown in Fig. 4, in which the stud end of locking set-screw 50' fits, the said screw fixes nut 45 in its proper alinement with relation to casing 25 and sleeve 40 in passing through both the stock of the casing and the nut, 120 these being provided with suitable tapped holes. It will be noted that the nut 45 is provided with suitable openings 48' for receiving a spanner wrench, while the flange 47 is also provided with corresponding 125 openings as shown in Fig. 4, said flange in addition being provided with notches 48 for receiving a small projection or wedge rigidly connected with the spring 49, which spring is fastened to the casing 25 by one 130

or more suitable screws 50 threaded into the casing 25. This spring extends for a suitable length and acts as points for the dial 52 on the cap 51 as well as locking means for preventing the accidental rotation of the head. The cap 51 is threaded on to the head 46 and is provided with a central opening 53 so as to freely admit air while a perforated, or very fine wire mesh disk 10 53 is used for preventing foreign matter from entering the head. The annular flange 47, preferably formed integral with the sleeve 38 is preferably of the same diameter as the casing 25, the location of the flange 15 47 being determined by the range of the adjustment required to close port 31. When the head 46, of which flange 47 and inner sleeve 38 form an integral part, is rotated in one direction a complete revolution, bushing 39' with its flange 39 will move together with sleeve 38 and valve 30 until the valve 30 is moved fully across the opening of port 31 bringing the notched flange 47 to bear against the end of casing 25 and 25 sleeve 40, said sleeve terminating at this point, in reversing the turning motion a full revolution the flange 39 is brought to bear against flange 41 showing a clearance between casing 25 and flange 47 equal to the 30 diameter of the port 31. It will thus be seen that both of the flanges 39 and 47 act as stops to the turning motion of the head 47 and any intermediate position will represent the degree of opening of port 31. In 35 connection with the valve 34 it will be noted that the same has a three-fold function, namely, it operates the valve member 30 so as to uncover port 31, as a valve member for permitting for a short time a small 40 quantity of air to enter in order that the suction may move the plunger or valve 30 and the graphite charges through the ducts, and also acts as means when head 46 is pulled out to cause plunger 30 to move to 45 a full open position as shown in Fig. 5. Unless some opening was provided back of the plunger or valve 30 the suction of the respective pistons would have no action on this valve, so that the arrangement of the 50 valve 34 is essential, and is such that when the suction begins to move the valve 30 it will also move valve 34 to a closed position. This back and forth movement is the normal operation of the system when the engine 55 is properly functioning. However, to help the priming of the engine when first starting the same the head 46, which is shaped as a handle, is pulled out as shown in Fig. 5 so that the port 31 will be fully 60 uncovered, thus permitting a maximum charge of graphite to enter each of the cylinders during the first few seconds of the operation of the engine. As the parts are pulled to the position shown in Fig. 5 a 65 maximum supply of graphite will be pro-

vided which will soon help to fill up the clearance present in the cold engine caused by the shrinkage of metal. The improved compression will cause a comparatively quick heating up of the engine to normal 70 operating conditions. As soon as the engine has properly picked up the head 46 is released and spring 44 will return the parts again to their normal position shown in Fig. 4. 75

The graphite as it passes into the engine is mixed with the inrushing gas as shown in Fig. 10, by reason of the fact that the inlet valve for the gas is opened at the same time as the automatic valve 22 whereby by 80 the inrushing gas the graphite will be carried around the walls of the cylinder where the graphite will absorb any free oil in its reach and thereby form a proper permanent heavy body of lubricant, excluding any 85 pernicious oil from the cylinders.

In providing a lubricating system embodying the invention it is aimed to construct the complete system at the factory and adjust the same to any particular type 90 of engine desired, after which the completed, adjusted device is shipped to the purchaser ready to be applied to the engine without a complicated operation. After having applied the various T-unions 14' in 95 place of the priming cups and then replacing the priming cups 15 on top of the T-unions the device is ready for operation. It will, of course, be understood that a proper supply of graphite of the proper 100 grade must be provided in reservoir 1, though the adjustment of any parts is not necessary.

To apply the lubricating system above described to a V-shaped type engine, the regulating mechanism with the reservoir is placed on a centrally located suitable bracket and is connected by the main supply ducts 54 and 55 into the T placed on the line pipes 3 and 4 (Fig. 11), which are 110 arranged on the same principle as shown in Figs. 1 and 2. The distribution of the graphite takes place on the same principle as in the four cylinder engines, as the firing of the two cylinders is always arranged to 115 take place on both sides of the crank shaft to actuate a well balanced operation of the engine, consequently the suction strokes by the pistons are taken in the same rotation thus dividing the graphite and causing the 120 same to move in both directions.

What I claim is:

1. A graphite lubricating system for internal combustion engines comprising a central container, a fitting for each cylinder of said engine, distributing pipes extending from the container to the respective fittings, a regulating member for regulating the discharge of graphite to said pipe, said regulating member being formed with means 130

for discharging graphite and air into said pipes simultaneously for a short time at the beginning of the suction stroke of the engine, said means closing before the suction stroke has been completed, and an automatic valve arranged in each of said fittings for preventing a loss in compression on the suction stroke.

2. A graphite lubricating system for internal combustion engines comprising a container, a fitting for each cylinder in said engine, distributing ducts extending from the container to the respective fittings, a regulating member for regulating the discharge of graphite to said ducts, said regulating member being formed with means for discharging graphite into said ducts and a small quantity of air simultaneously therewith, an automatically actuated valve for shutting off the air to said ducts immediately after the discharge of the graphite into said ducts whereby only a sufficient amount of air is admitted to said ducts to permit the passage of the graphite to the engine, and an automatically actuated valve arranged in each of said fittings for preventing a loss in compression.

3. A graphite lubricating system for internal combustion engines comprising a reservoir, means for guiding graphite to the respective cylinders from the reservoir, and means for regulating the passage of graphite from the reservoir to said guiding means, said regulating means comprising a casing having a feeding passageway merging into a discharge bore, a valve member slidingly mounted in the discharge bore and positioned to move across the opening of the feeding passageway, rotatable means for adjusting said valve member micrometrically back and forth in said bore across said passageway, and manually actuated means for bodily moving said valve member longitudinally of said bore away from said feeding passageway.

4. A graphite lubricating system of the character described comprising a supply reservoir, a system of piping for leading graphite to the various cylinders of an engine, and means for regulating the supply of graphite leaving said reservoir, said means comprising a casing having a comparatively small passageway and a valve bore into which the supply passageway merges, a sliding valve member leading into said bore and positioned to close said passageway when in a predetermined position, a sleeve fitting into said casing, a valve stem fitted on said valve, said stem fitting in said sleeve, a spring surrounding said stem and acting on one end thereof and on said sleeve, a second sleeve threaded over the first mentioned sleeve, a spring for normally holding the second sleeve in a given position, a head connected with the first mentioned sleeve,

said head being manually operated against the action of said second mentioned spring whereby the valve member is bodily moved away from said passageway, and means for locking said sleeve against rotation.

5. In a graphite lubricating system of the character described, a system of piping leading to the various cylinders of the engine, a supply reservoir for supplying graphite to said piping, and a regulating construction for regulating the passage of graphite from the reservoir, said regulating construction comprising a casing having a feeding passageway and a valve bore, said feeding passageway merging into the valve bore, a cylindrical valve member slidably fitted in said valve bore adapted to open and close said passageway, a rotatable manually operated head, means for connecting the head with said valve member in such a manner that when the head is rotated the valve member will be adjusted longitudinally of said bore for opening or closing to a greater or less extent said passageway according to the degree of movement of said head, and a locking spring carried by the casing engaging part of the head for locking same against accidental rotation.

6. A graphite lubricating system of the character described comprising a system of piping leading to the various cylinders of an engine, a supply reservoir for supplying graphite to said piping, and a regulating construction for regulating the passage of graphite from the reservoir into said piping, said regulating construction comprising a casing having a feeding passageway, a valve member for opening and closing said passageway, a rotatable manually operated head, a sleeve connected with said head having an externally threaded section and a flange, a reciprocating sleeve arranged in said casing threaded on to said threaded section and extending to near one end of the casing whereby when the head is turned in one direction the sleeve and its flange will press against the sliding sleeve, and when the head is rotated in the opposite direction the flange of said sleeve will engage the casing which acts as a stop therefor whereby the movement of said valve is limited to correspond to the diameter of said feeding passageway, and a spring for normally holding said sliding sleeve in a given position.

7. An automatically operated graphite lubricating system for combustion engines comprising a container for graphite formed with a discharge port arranged at an angle, a feeding mechanism provided with a plunger positioned to close said port, manually actuated means for setting said plunger to feed a predetermined amount of graphite, said manually actuated means being operable to fully open said port for priming purposes, and means for guiding

the graphite fed through said port to the cylinders of said engine, said means including a valve mechanism for each cylinder of the engine for preventing loss of compression of the respective cylinders.

8. An automatically operated graphite lubricating system for combustion engine cylinders comprising a single container, ducts extending from said container to each cylinder of said engine, a manually regulated member for controlling the passage of graphite from said container, said member

being operable manually for priming purposes, and means connecting said ducts for connecting the ducts with the respective cylinders, said means including an automatic valve for each cylinder formed to open on the suction stroke of the cylinder and to close automatically at the end of said suction stroke whereby no loss of compression is permitted while free entrance of the graphite is allowed.

JOHN D. LOOG.
